(57) **CLAIM**

The ornamental design for an auxiliary power interface for a portable illuminator assembly, as shown and described.

DESCRIPTION

FIG. 1 is a bottom perspective view of an auxiliary power interface for a portable illuminator assembly, illustrating our new Design;

FIG. 2 is a front side view thereof;

FIG. 3 is a left side view thereof;

FIG. 4 is a right side view thereof;

FIG. 5 is a back view thereof;

FIG. 6 is a bottom view thereof;

FIG. 7 is a top plan view thereof; and,

FIG. 8 is a front side view of FIG. 2 in a usage condition.

The broken line portion of FIGS. 1 through 5 and FIG. 7 is included to show the unclaimed cable; the broken line shown in FIG. 8 shows the unclaimed cable and also the unclaimed portable illuminator. All of the subject matter rendered in broken line is unclaimed and forms no part of the claimed design.

1 Claim, 2 Drawing Sheets
